WINDOW

Samuel C. Reynaud, Detroit, Mich., assignor to
 Detroit Steel Products Company, Detroit,
 Mich., a corporation of Michigan

Application February 29, 1932, Serial No. 595,884

6 Claims. (Cl. 189—69)

The invention relates to windows and has for one of its objects to provide an improved construction of window having lock controlled means providing for and limiting the opening movement 5 of the sash, whereby the window may be used as a detention window, if desired. Another object is to so construct the window that the means for limiting the opening movement of the sash may be made inoperative, so that the sash may be 10 more fully opened, if desired, to enable cleaning or the like of the window. A further object is to so construct the window and the means for limiting the opening movement of the sash that the parts may be readily and economically assembled. 15

These and other objects of the invention will become apparent from the following description, taken in connection with the accompanying drawings, in which

20 Figure 1 is a perspective view of a portion of a window showing an embodiment of my invention;

Figure 2 is a vertical section therethrough; Figures 3 and 4 are cross sections on the lines 25 3—3 and 4—4, respectively, of Figure 2 with the sash in closed position;

Figure 5 is a perspective view of a window showing another embodiment of my invention;

Figure 6 is an inside elevation of a portion 30 thereof;

Figure 7 is a view similar to Figure 6, showing another embodiment of my invention;

Figure 8 is a cross section on the line 8—8 of 35 Figure 7.

While the invention is equally applicable to various types of windows, such as those having side hinged open out and open in sashes or ventilators, or those having sashes or ventilators which are adapted to be projected out or projected in, as well as still other types, the invention as shown in Figures 1 to 4 inclusive is applied to a window of the projected out type. This window comprises the metallic frame 1 and the metallic sash 2 between the jamb bars of which 40 extend the supporting arms 3 having their opposite ends pivotally connected to the jamb bars. The upper portion of the sash 2 is pivotally and slidably connected to the frame as by means of the shoes 4 pivotally mounted upon the sash and 45 slidably engaging the jamb bars of the frame. With the exception that the supporting bars 3 are shorter and pivotally connected to the jamb bars of the frame at a greater height, the above described construction of window is the same as 50 the ordinary construction of this type.

5 is an arm having its upper end pivotally and slidably connected to a jamb bar of the sash 2. In detail, the upper end of this arm has secured thereto the shouldered rivet 6 which slides in the slot 7 formed in and extending longitudinally 5 of the metallic guide 8, which latter extends longitudinally of the jamb bar of the sash and is fixedly and permanently secured to its web by suitable means, such as the rivets 9. 10 is a bracket fixedly and permanently secured to the 10 web of the adjacent jamb bar of the frame 1 as by the rivets 11. The portion of this bracket through which the rivets pass is spaced laterally from the jamb bar of the frame by the block 12, which extends longitudinally of the jamb bar. 15 The bracket has the lower end portion 13 which is laterally offset from the block 12 and is adapted to extend adjacent to the lower end of the arm 5. This offset portion has the transverse hole 14 which is of a size to fit the cylindrical portion 16 of the shouldered rivet 17, the latter extending transversely of and being secured to the lower end of the arm 5. The rivet 17 has the head 18 at its free end which is adapted to extend into the opening 19 in the lower end 20 of the block 12. 25

With the construction as above described, it will be seen that when the arm 5 is operatively connected to the frame 1 through the shouldered rivet 17 and the bracket 10 the sash 2 may open to an extent controlled by the arm 5. This arm is of such a length that the size of the opening is less than that required for the passage therethrough of a human being. On the other hand, if it is desired to more fully open the sash for the purpose of cleaning the same or for any other reason the arm 5 can be disconnected from the frame and made inoperative by moving the lower end of the arm laterally a sufficient distance to disengage the rivet 17 from the bracket 10, there 40 being sufficient play to provide for this disengagement. The arm 5 is preferably made of substantially tool-proof material, such as spring steel, so that when this arm is locked it is very difficult for any one to cut his way out by the use 45 of a hack-saw or other tool.

20 is a latch having the body portion 21 longitudinally slidable of the jamb bar between the offset portion 13 of the bracket and the block 12. This latch has at the lower end of its body 50 portion the transverse flange 22 and has in its body portion the key-hole shaped opening 23 having an enlarged portion at its upper end of a size to permit the passage of the head 18 of the rivet therethrough and also having a re- 55

duced portion at its lower end of a size to clear the neck of the rivet 17 between its enlarged portion 16 and its head 18. The size of this reduced portion of the opening, however, is such that when the neck of the rivet extends through this reduced portion the head cannot be disengaged from the latch. For controlling this latch, I have provided the lock 24 having the housing 25 fixedly and permanently secured to the frame 1 at the lower end of its jamb bar. The lower end portion of the latch extends into and is guided by the housing. The lock also has controlling mechanism comprising the cylinder 26 and the cam 27. The cylinder has its stationary part fixedly and permanently secured within the housing as by being welded thereto at 28 and its movable part, which is located within the stationary part and connected at one end to the cam 27, extending inwardly through the inside 10 flange of the lower or sill bar or the horizontal meeting rail of the frame immediately below the opening, whereby this movable part may receive a key. The cam 27 is adapted to be rotated from the position shown in full lines in Figure 3 to the position shown in dotted lines in the same figure and this cam is engageable with the transverse flange 22 of the latch, so that when the cam is in the position shown in full lines the latch is in its uppermost position and positively secures the arm 5 to the frame 1 and when the cam is in the position shown in dotted lines the latch is in its lowermost position, at which time the enlarged portion of the opening 30 25 of this latch registers with the head 18 of the rivet 17 and provides for disengagement of this rivet from the bracket 10.

It will be seen that all of the parts which provide for and limit the opening movement of the sash are located in the space formed between the bars of the frame and the sash when the sash 40 is in closed position, with the exception that the portion of the cylinder into which the key may be inserted is exposed.

In the modification shown in Figures 5 and 6, the invention is shown as applied to a window having a sash movable horizontally to open position. This window may be of the side-hinged or side-projected type and, as shown, is a casement window. In detail, the window has the frame 29 45 and the outwardly opening sash 30 hinged upon the frame. The mechanism for limiting the outward swinging movement of the sash is the same as that previously described in connection with Figures 1 to 4, inclusive, with the exception that the arm 31 is pivotally and slidably connected to the bottom or sill bar of the sash 30 and is adapted to be pivotally connected to the bracket 32, which latter is permanently fixedly secured to the bottom or sill bar or the horizontal meeting rail of the frame 29 immediately below the sash when closed. The locking device for controlling the securing of the arm to the bracket is also mounted upon the same bar or rail and all of this mechanism is located within the space 50 formed by the frame and sash bars when the sash is closed, with the exception that the portion of the locking device which is adapted to be engaged by the key extends inwardly through the inside flange of this bar or rail.

Figures 7 and 8 disclose another modification in which the latch 33 is adapted to be secured in its adjusted positions by the locking member 34, which is a special screw having the enlarged head 35 at its upper end, the cylindrical portion 70 75 36 extending through an elongated slot in the

latch and the threaded portion 37 threaded into the web of the lower or sill bar or horizontal meeting rail immediately below the window opening. The head 35 may be provided with a special wrench engaging socket, such as the polygonal recess 38, so that this locking device can only be operated by means of a special wrench. For assisting in locking the latch, I have provided the normally bowed spring washer 39 which is located between the latch and the web of the bar 10 or rail.

What I claim as my invention is:

1. In a window construction, the combination with a frame and a sash on said frame normally movable to a predetermined open position, of a bracket upon one of said members and an arm operatively connected to the other of said members and adapted to be operatively connected to said bracket providing for and limiting the opening movement of said sash to an open position between said predetermined open position and the closed position, a latch movable to a position to secure said arm to said bracket and also movable to a position to provide for disconnecting said arm from said bracket, and locking means 25 for controlling said latch.

2. In a window construction, the combination with a frame and a sash on said frame normally movable to a predetermined open position, of a member upon one of said frame and sash members and an arm operatively connected to the other of said frame and sash members and adapted to be operatively connected to said first mentioned member providing for and limiting the opening movement of said sash to an open position between said predetermined open position and the closed position, a latch for detachably securing said arm to said first mentioned member, and spring means engageable with said latch for frictionally resisting movement thereof. 40

3. In a window construction, the combination with a frame member and a swinging sash member, of means for limiting movement of the sash member to open position including an arm having one end slidably and pivotally connected to 45 one of said members, means for slidably and pivotally connecting the other end of said arm to the other of said members, said last named means fashioned to provide for detaching the associated end if the arm from the latter member upon sliding movement of said end to a predetermined position relative to the member, and a key-operated lock preventing unauthorized removal of the arm from said last named member. 50

4. In a window construction, the combination with a frame and a swinging sash on said frame, of means for limiting movement of the sash to open position including an arm having one end pivotally and slidably connected to the sash, means pivotally and slidably connecting the other end of the arm to the frame fashioned to provide for detaching the arm from the frame upon sliding movement of the last named end thereof to a predetermined position relative to the frame, and a lock carried by the frame preventing unauthorized sliding movement of said last named end of the arm to detach the same from the frame. 65

5. In a window construction, the combination with a frame and a sash mounted on said frame, of means for limiting the movement of the sash to open position including an arm having one end pivotally connected to said sash and having the opposite end detachably mounted upon the frame and a key operated lock also carried by the 70 75 75

- frame and cooperating with the connection between the arm and frame to prevent unauthorized removal of said arm from the frame.
6. In a window construction, the combination with a frame and a sash mounted on said frame for movement relative thereto, of means for limiting movement of the sash including an arm having one end operatively connected to the sash and carrying an attaching member at the opposite end, said member having a reduced portion extending transversely of the arm and provided with an enlarged head portion, a bracket fixed to the frame having an opening of sufficient dimension to receive the enlarged head portion and having an extension of sufficient width to receive the reduced portion of said member and being of less width than the corresponding dimension of the head portion in order to retain the arm in assembled relation with the frame, and means preventing unauthorized movement of the arm relative to the bracket to disengage the former from the latter.
